UNITED STATES PATENT OFFICE.

RUEL H. LUNT, OF SOUTH WILLIAMSPORT, PENNSYLVANIA.

RAILWAY-SPIKE.

1,187,351.

Specification of Letters Patent. Patented June 13, 1916.

Application filed December 31, 1915. Serial No. 69,634.

To all whom it may concern:

Be it known that I, RUEL H. LUNT, a citizen of the United States, residing at South Williamsport, in the county of Lycoming and State of Pennsylvania, have invented 5 certain new and useful Improvements in Railway-Spikes, of which the following is a specification.

This invention relates to railway spikes. 10 The objects of the invention are to provide a spike that may readily be seated and be thoroughly effective in holding a rail in place, and which may, with comparative ease, and without injury to the sleeper, be 15 removed when necessary; to construct the point in such manner as to cause it readily to penetrate a sleeper without undue rupture of the grain thereof and of a contour that will insure a close contact between the point 20 and wood through its entire length as well as with the shank; and generally to present a spike in which any weakening of the shank to secure a positive interlocked relation with the sleeper will positively be precluded.

25 In carrying the invention into practice, there is provided a spike having the usual or any preferred form of head, and a shank preferably quadrangular in cross-section.

The novelty of the invention resides in 30 the novel construction of the spike point and of the sides of the shank adjacent thereto, the result secured being the easy seating of the spike, its positive retention in place against danger of working loose from jars 35 and vibrations, and the facility with which the spike may be withdrawn from the sleeper. These results are attained by forming the spike point of curvilinear spear-head contour and the sides of the spike adjacent 40 to the head, on curvilinear lines defining thereby shoulders that are curved downwardly and outwardly on relatively short arcs, the transverse diameter of the shoulders at their juncture with the point being 45 equal to the like diameter of the shank, and the curves of the point and sides being struck from alined centers equally distant from the longitudinal axis of the spike shank. The effect of this arrangement is 50 that when the spike is seated, the point will not make an opening larger than the shank, so that there will be an intimate contact between the sleeper and the spike throughout the entire length of the latter, and owing 55 to the disposition and contour of the shoul-

ders, the wood will close tightly around the latter and thus accentuate the holding capacity of the spike. In addition, the shoulders operate to facilitate the removal of the spike, inasmuch as they act as wedges 60 to exert lateral thrust on the wood so that any rupture of the walls of the spike opening is prevented.

Further features of novelty will herein-after appear.

65 In the accompanying drawings: Figure 1 is a longitudinal sectional view showing the spike seated in a sleeper; Fig. 2 is a dia-grammatic view of the spike.

The spike embodies a head 1 of any pre- 70 ferred shape, a shank 2, preferably quad- rangular in cross section, and a point 3 of curvilinear spear-head contour. From the point *d* the two opposite sides of the shank are curved inward to the point *c*, thence 75 curved outward from *c* to *b* forming thereby shoulders 4, and the opposite sides of the point are curved inward from *b* to *a* defining the spear-head contour, the curves *a* *b* and *c* *d* being struck from alined centers equally 80 distant from the longitudinal axis of the spike.

When the spike is being seated the point will cut instead of crush its way, thus forming a spike opening having comparatively 85 smooth walls, and when the spike is driven home, the wood will fill in around the shoulders, as shown in Fig. 1. When the spike is removed, the shoulders will exert a lateral thrust on the wood and thus facilitate with- 90 drawal.

What is claimed is:

A railway spike shank having a point of curvilinear spear-head contour and curvi- 95 linear sides adjacent to the point defining shoulders that are curved on relatively short lines curved downwardly and outwardly, the transverse diameter of the shoulders at their juncture with the point being equal to the like diameter of the shank, whereby to 100 secure easy seating of the spike and the curves of the point and sides being struck from centers equally distant from the longi- tudinal axis of the spike.

In testimony whereof I affix my signature 105 in presence of two witnesses.

RUEL H. LUNT.
